UNITED STATES PATENT OFFICE.

ROBERT NAYSMITH, OF PITTSBURG, PENNSYLVANIA, ASSIGNOR OF ONE-HALF TO ARTHUR J. WILKINSON, OF SAME PLACE.

APPARATUS FOR THE PRODUCTION OF GAS.

SPECIFICATION forming part of Letters Patent No. 403,283, dated May 14, 1889.

Application filed August 4, 1888. Serial No. 281,988. (No model.)

To all whom it may concern:

Be it known that I, ROBERT NAYSMITH, a citizen of the United States, residing at Pittsburgh, in the county of Allegheny and State of Pennsylvania, have invented certain new and useful Improvements in Apparatus for the Production of Gas, of which improvements the following is a specification.

My invention relates to apparatus for the manufacture of heating and illuminating gas of the class in which steam, air, and the volatile constituents of oil are combined in suitable proportions, and by the application of a proper degree of heat a fixed gas is generated; and the object of the invention is to provide an apparatus of such known general type which can be readily and inexpensively erected and renewal or repair of its members effected, as from time to time required, and in the operation of which a more thorough and perfect combination and utilization of the gas-generating elements may be attained than has heretofore been ordinarily practicable.

To this end my invention consists in certain novel devices and combinations herein-after fully set forth.

In the accompanying drawings, Figure 1 is an end view, in elevation, of a gas-generating apparatus embodying my invention; Fig. 2, a vertical longitudinal section through the same, and Fig. 3 a sectional view illustrating a modification of the distributor of the feed or mixing box.

In the practice of my invention I provide a suitable furnace, 3, which may be heated by either solid or gaseous fuel and support upon its opposite sides or ends a feeding or distributing box or case, 1, and a separating or delivery box, 2. The boxes 1 and 2 are connected by a multiple series of tubular retorts, 4, of comparatively small diameter, in order to provide as large an amount of heating-surface as practicable, said retorts passing through the furnace and having their ends fitted into corresponding openings in the adjacent walls of the boxes 1 and 2, their joints with which are packed with asbestos or other suitable refractory material. The retorts 4 are supported by iron frames 5, secured detachably to the walls of the furnace by bolts, and the boxes 1 and 2 are similarly secured to the frames 5.

The boxes 1 and 2 are provided with removable cover-plates 6 and 7, by which access to the retorts is permitted for inspection, cleaning, or other purposes, and the cover-plate of the separating-box 2 is provided with a man-hole closed by a suitable plate, 8, to admit of the removal of such residuum as may not escape through a trap, 9, which is connected to the lower end of the box and to a pipe leading to a proper receptacle. The separating-box 2 is likewise provided with a discharge-pipe leading to a gas-holder, 10, for the collection and subsequent distribution of the gas produced.

Two U-shaped superheaters, 11 12, are supported in the furnace 3 above the retorts 4, one of which, 11, serves for the superheating of steam, and the other, 12, for that of air. A steam-supply pipe, 13, leading from a boiler, is connected to one end of the steam-superheater 11, the opposite end of which is connected by a pipe, 14, with the feeding or distributing box 1. An air-supply pipe, 13^a, leading from a blower or other suitable source of supply of air under pressure, is connected to one end of the air-superheater 12, the opposite end of which is connected by a pipe, 14^a, with the feeding or distributing box. An oil-supply pipe, 15, is led into the pipe 14, the oil supplied through the pipe 15 being vaporized by the superheated steam passing through the pipe 14 and entering the box 1 therewith.

In order to distribute the mingled air, steam, and oil conducted into the box 1 by the pipes 14^a, 14, and 15 with substantial uniformity to the several retorts 4 of the multiple series connected to the boxes 1 and 2, curved deflector-plates 16 are secured to the inner wall of the box 1, the action of which plates is to divide and distribute the currents of air, steam, and oil-vapor throughout the series of retorts, thereby effecting a more thorough commingling and distribution for heating of these elements. In lieu of the deflector-plates, a fan, 17, may, as shown in Fig. 3, be mounted in a bearing in the box 1 in such position as to be rotated by the entering currents of air, steam, and oil-vapor, and by such rotation to effect their commingling and distribution.

In the passage of the commingled air, steam, and vaporized oil through the series

of retorts they are subjected to the heat of the furnace, which, by reason of the large extent of surface and subdivision of the currents afforded by the provision of a series of 5 tubular retorts of small diameter, is thoroughly and effectively applied and the loss of hydrocarbon elements materially reduced as compared with the ordinary practice. The resultant fixed gas passes from the retorts, 10 through the box 2, into the holder, and any residuum which may be separated is collected in the box 2, and, dropping to the bottom, flows out through the trap 9, or may be removed through the man-hole.

15 To facilitate the manufacture, two separate series of retorts, each connected to a distributing and a separating or delivery box, are preferably employed, in which case the superheaters 11 and 12 are connected with 20 each of the distributing-boxes 1, as shown in Fig. 1, and each of the separating or delivery boxes is connected to the gas-holder 10. Under such construction the manufacture of gas may be conducted by the employment of one 25 series of retorts while the other is under repair or otherwise temporarily out of use. It will be seen that as each retort is supported by the frames 5 independently of the others the removal of the box 1 from its frame admits 30 of the removal and insertion of one or more retorts, as may be required, without interference with the remaining retorts of the series. Further, in the event of the destruction of one of the retorts, the cover-plates 6 35 and 7 of the boxes 1 and 2 may be removed and the ends of the broken retort suitably plugged.

In order to insure the separation and collection of any unvaporized oil which may be 40 carried into the separating-box 2 with the gas, a deflecting-plate, 18, is secured at its top to the inner wall of the box 2, above the upper row of retorts, and extends downwardly below the lower row, said plate deflecting the 45 products passing out of the retorts toward the bottom of the box, the gas passing upwardly on the outer side of the deflecting-plate, and the residuum being deposited on the bottom of the box, whence it passes off 50 through the trap 9, or is withdrawn through the man-hole.

I am aware that apparatus embodying a gas-generating retort adapted to be supplied with oil and with air and steam led into the 55 retort from separate superheaters was known in the art at the date of my invention, and said devices, as well as their combination, broadly, I therefore distinctly disclaim. I am not, however, aware that the structural features of improvement which characterize my invention, as herein described and shown, have been heretofore either proposed or employed, nor that the useful results produced thereby have been equally attainable under 60 prior constructions.

I claim as my invention and desire to secure by Letters Patent—

1. In a gas-producing apparatus, the combination of a furnace, a feeding-box and a delivery - box fixed, respectively, on opposite sides of said furnace, a multiple series of tubular retorts passing through the furnace and communicating at their opposite ends with the feeding and delivery boxes, and an oil-pipe, a steam-pipe, and an air-pipe, each leading into the feeding-box, and frames fixed to the sides of the furnace and supporting said retorts adjacent to their ends and independently one of the other, substantially as set forth. 70 75 80

2. In a gas-producing apparatus, the combination of a furnace, a feeding-box and a delivery - box fixed, respectively, on opposite sides of said furnace, a multiple series of tubular retorts passing through the furnace and communicating at their opposite ends with the feeding and delivery boxes, an oil-pipe, a steam-pipe, and an air-pipe, each leading into the feeding - box, and frames fixed to the sides of the furnace and supporting said 90 retorts with the capacity of independent insertion and removal upon the detachment of the feeding-box, substantially as set forth. 95

3. In a gas-producing apparatus, the combination of a furnace, a feeding-box and a delivery - box fixed, respectively, on opposite sides of said furnace, a multiple series of tubular retorts passing through the furnace and communicating at their opposite ends with the feeding and delivery boxes, an oil-pipe, 100 a steam-pipe, and an air-pipe, each leading into the feeding-box, and a mixer and distributor located within the feeding-box, substantially as set forth. 105

4. In a gas-producing apparatus, the combination of a furnace, a feeding-box and a delivery - box fixed, respectively, on opposite sides of the furnace, a multiple series of tubular retorts passing through the furnace and communicating at their opposite ends with the feeding and delivery boxes, an oil-pipe, a steam-pipe, and an air-pipe, each leading into the feeding-box, a discharge-pipe leading out of the upper portion of the delivery-box, and a deflecting-plate projecting downwardly in the delivery-box between the ends 110 115 of the retorts and the discharge-pipe, substantially as set forth.

5. In a gas-producing apparatus, the combination of a furnace, two separate series of tubular retorts passing through the furnace, the retorts of each series communicating at their opposite ends with a feeding-box and a delivery-box, respectively, steam and air superheaters located in the furnace and communicating by pipes with the feeding-boxes of both series of retorts, and oil-pipes leading into 120 125 130 said feeding-boxes, substantially as set forth.

In testimony whereof I have hereunto set my hand.

ROBERT NAYSMITH.
